US0D1023803S

(12) **United States Design Patent** (10) **Patent No.:** **US D1,023,803 S**
(45) **Date of Patent:** **** Apr. 23, 2024**

(54) **DETECTOR**

(71) Applicant: **Tongxue Technology (Shenzhen) Co., Ltd.**, Shenzhen (CN)

(72) Inventors: **Jiahao Jiang**, Nanning (CN); **Yongsheng Wang**, Shenzhen (CN)

(73) Assignee: **Tongxue Technology (Shenzhen) Co., Ltd.**, Shenzhen (CN)

(**) Term: **15 Years**

(21) Appl. No.: **29/860,577**

(22) Filed: **Nov. 21, 2022**

(30) **Foreign Application Priority Data**

Jun. 24, 2022 (CN) 202230393954.9

CLAIM

The ornamental design for a detector, as shown and described.

DESCRIPTION

FIG. 1 is a front perspective view of a detector, showing our new design;

FIG. 2 is a bottom, rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the detector, which form no part of the claimed design.

1 Claim, 8 Drawing Sheets
